UNITED STATES PATENT OFFICE.

ARTHUR SPYER, OF LONDON, ENGLAND, ASSIGNOR TO THE BABCOCK & WILCOX COMPANY, OF BAYONNE, NEW JERSEY. A CORPORATION OF NEW JERSEY.

STEAM BOILER.

Application filed February 14, 1925. Serial No. 9,069.

To all whom it may concern:

Be it known that I, ARTHUR SPYER, a subject of the King of Great Britain, and resident of No. 13° Hyde Park Mansions, Marylebone Road, London, England, have invented certain new and useful Improvements in Steam Boilers, for which I have filed application in Great Britain, Serial No. 1,259, Jan. 16, 1924, and of which the following 10 is a specification.

My present invention relates to steam boilers, particularly boilers provided with both superheaters and reheaters in which it is desirable to have not only a compact arrangement, but one in which the degree of reheating may be controlled.

My invention will be best understood from the following description and the annexed drawings, in which Fig. 1 is a vertical section of a boiler embodying my invention; Fig. 2 is a vertical elevation of the boiler shown in Fig. 1; Fig. 3 is a rear elevation of Fig. 2, with a portion of the boiler shown in section on line 3—3 of Fig. 2; Figs. 4, 5 and 6 are views similar to Fig. 1, showing modifications, and Fig. 7 is a vertical sectional view of a double boiler embodying my invention.

Like reference characters indicate like parts in the several views.

Referring to the arrangement shown in Figs. 1, 2 and 3, the boiler has a furnace chamber 10 over which is placed a lower bank 11 of horizontally inclined water tubes 12 and spaced therefrom vertically an upper bank 12, with the tubes parallel to those of the bank 11.

The lower bank 11 has downtake headers 13 and uptake headers 14 connected respectively by pipes 15 and 16 with a steam and water drum 17, the pipes 15 and 16 being outside of the setting, in the illustrative embodiment.

The upper bank 12 has downtake headers 18 and uptake headers 19 connected respectively by nipples 20 and tubes 21 with the steam and water drum 17.

In the space between the banks 11 and 12 is a superheater 22 having an inlet header 23 and an outlet header 24, the former being connected by a pipe 25 to the drum 17. A superheater such as described, may be provided extending in from either side of the boiler, as shown in Fig. 3, in such case, the

pipe 25 being duplicated at the opposite ends of the drum 17.

Above the superheater 22 is a reheater 26 having drums 27 on opposite sides of the setting, the steam to be reheated entering one of these drums and leaving the other drum through pipes 28, the tubes of the reheater extending, in the illustrative form, across the entire setting.

Above the high ends of the tubes of the bank 11 is a fixed baffle 29, above the inner end of which is a vertically slideable baffle 30 suspended on flexible members to a shaft 31 controlled by a hand chain 32 from the exterior of the boiler.

Above the reheater 26 and at the low ends of the tubes of the upper bank 12 is a fixed roof baffle 33, from the inner end of which extends upwardly a transverse baffle 34, a second transverse baffle 35 extending downward across some of the tubes of the upper bank 12.

With the parts shown in the position of Fig. 1, the gases from the furnace 10 pass across the bank 11, then over the superheater 22, from thence to the right of the figure to the high ends of the bank 12, and from thence back and forth across these water tubes to the gas exit 36.

If the baffle 30 is dropped to its lowermost position, the gases will pass over the reheater 26 instead of being diverted therefrom, as is the case when the baffle is in the position shown in Fig. 1, and obviously any intermediate position of the baffle 30 will regulate the quantity of the gases passing over the reheater 26 while at the same time, the total amount of gases always pass over the superheater 22.

By the arrangement described, the superheater and reheater are subjected to gases which have passed over one bank only of water tubes and the degree of reheating may be readily controlled from the exterior of the boiler. Moreover, by reason of the separate connections between the two banks to the steam and water drum, the boiler may be driven at high ratings without possibility of disturbance of the circulation in either bank.

The arrangement shown in Fig. 4 is similar to that of Fig. 1, except that the positions of the reheater 26 and the superheater

22 are reversed and both are placed over the roof baffle 29, so that the reheater may be subjected to gases before they have contacted with the superheater. In this arrangement, 5 as in Fig. 1, however, all of the gases will pass over the superheater, regardless of the position of the baffle 30.

In the arrangement shown in Fig. 5, the banks of tubes are the same as in Figs. 1, 2 10 and 3, except that they are inclined in opposite directions, the connections to the steam and water drum being the same as in Figs. 1, 2 and 3.

The superheater 22 and the reheater 26 15 are arranged side by side in the space between the pair of banks and the baffle 30 is movable vertically between them.

In this arrangement, the gases from the furnace pass across the lower bank 11 and 20 then across the superheater 22. With the baffle in the position shown in Fig. 5, the gases then turn to the left and pass over the reheater 26 and from thence flow upward and back and forth across the upper tubes 25 12 as before.

When the baffle 30 is lowered to its lowermost position, the gases are diverted from the reheater 26 and any intermediate position of the baffle 30 will determine the proportion 30 of the gases which will flow over the reheater.

In the arrangement shown in Fig. 6, the tubes of the lower bank 40 are connected to downtake headers 41 and uptake headers 42, these banks being connected as before and as best shown in Fig. 3, through separate downcomers and upcomers with the water drum 43. The upper bank 44 has its tubes parallel to the tubes of the bank 40 40 and its downtake headers 45 and uptake headers 46 are connected by nipples and tubes in the usual manner to the drum 43. A row of tubes 47 connects the upper part 45 of the downtake headers 41 with the lower part of the uptake headers 46 and another row of tubes 48 similarly connects the upper part of the downtake headers 41 with the lower part of the uptake headers 46, the tubes 47 and 48 being spaced apart quite 50 widely at their right-hand ends.

A fixed roof baffle 49 extends above the lower bank 40 and above this roof baffle is the reheater 50 which has the same construction as before described. At the right of the reheater 50 is a superheater 51, which also has the same construction as before described, the steam entering the superheater from the drum 43 through the pipe 52.

Slidingly supported on the tubes 47 is a 60 movable baffle 53 connected by flexible members to the shaft 54 operated by the hand chain 55 from the exterior of the boiler.

With the parts in the position shown in Fig. 6, the gases first pass across the lower bank 40 and then across the superheater 51

and the rows of tubes 47 and 48 and enter the high end of the bank 44, from which they flow back and forth by reason of the transverse baffles 56, 57 to the gas exit 58, a fixed roof baffle 59 supported on the tubes 70 48 directing the gases to this high end of the upper bank.

In the position of the movable baffle 53 shown in Fig. 6, the gases are diverted from the reheater 50. If the baffle 53 be moved 75 to the right of Fig. 6, then the gases, after passing over the superheater 51, will pass over the reheater 50 and around the inner end of the baffle 53 into the high end of the water tubes 44. Any intermediate position 80 of the baffle 53 will determine the proportion of the gases passing over the reheater 50, the total amount passing at all times over the superheater 51.

It will be noted that the arrangement 85 shown in Fig. 6 provides not only the most compact arrangement, but also provides for the hot gases being directed into the high ends of the horizontally inclined water tubes, so that the best arrangement is provided for the generation of steam, and, at the same time, the degree of reheating may be regulated as desired without affecting the amount of heat delivered to the superheater. 95

In the arrangement shown in Fig. 7, the boiler is a double one, having three upper steam and water drums 60, 61 and 62, the lower banks 63, 63 being connected at their high ends to a central drum 64 and at their 100 low ends to downtake headers 65, 65. Each of the upper banks 66, 66 has downtake headers 67, 67 and uptake headers 68, 68, each connected in the usual manner to a drum 60 or 62, respectively, these drums, in turn, being connected by suitable tubes to the central drum 61. The downtake headers 65 are connected to one of the drums 60, 62 by pipes 68, 68 and the drum 64 is connected to the drum 60 by a plurality of rows 110 of tubes 70 (two of such rows being shown) connects the drums 61 and 64 inside of the setting.

The baflling and superheater and reheater arrangements in each of the parts of the double boiler are the same, and a description of one of them will be sufficient. 115

A fixed roof baffle 71 extends from the downtake headers 68 toward the center of the boiler, and above this baffle is a reheater 72 of the same construction as that heretofore described. On the opposite side and substantially in horizontal alignment with the reheater is a superheater 73, also of the same construction as that heretofore described. 120

The upper bank 66 is provided with a fixed roof baffle 74 and transverse baffles 75, 76.

Arranged to slide vertically between the 130

reheater and superheater is a movable baffle 77 controlled by a hand chain from the exterior of the boiler and the position of this movable baffle will determine the quantity 5 of the gases passing over the reheater 72.

It will be understood that in the arrangement of Fig. 7, the two parts of the superheater are connected in parallel with the steam and water drum of the boiler and that 10 the two parts of the reheaters are also preferably connected in parallel.

It will be understood that the arrangements which are shown are merely illustrative and that the constructions may be 15 widely varied and also that certain features of the arrangement may be used either with or without the other features illustrated.

I claim:

1. A steam boiler having banks of water 20 tubes, said banks being spaced apart to form a superheater chamber therebetween, fixed baffles to direct the furnace gases from one end of one bank across such space into the other bank, a pair of heating devices in 25 said space, a movable baffle in said space and movable into either one of two extreme positions, said movable baffle in one extreme position being interposed in the path of the gases normally flowing across said space 30 and across one of said heating devices, and in the other extreme position being positioned to direct all of the gases first across all of one of said heating devices and then across all of the other of said heating devices, and means to move said movable baffle. 35

2. A steam boiler having banks of water tubes, said banks being spaced apart to form a superheater chamber therebetween, fixed baffles to direct the furnace gases from one 40 end of one bank across such space into the other bank, a pair of heating devices in said space and each comprising a plurality of rows of tubes, a movable baffle in said space and removed from said heating devices, said 45 movable baffle being movable into either one of two extreme positions, said movable baffle in one extreme position being interposed in the path of the gases normally flowing across said space and across one of said heating devices, and in the other extreme position being positioned to direct all of the gases first 50 across all of one of said heating devices and then across all of the other of said heating devices, and means to move said movable baffle. 55

3. A steam boiler having banks of horizontally inclined water tubes, said banks being spaced apart to form a superheater chamber therebetween, a superheater and a 60 reheater in such space, fixed baffles above and below said space to direct the gases in a path from one end of the lower bank across said superheater and across said reheater to one end of the other bank, and a movable baffle in said space and movable into and

out of the path of the gases flowing across said reheater while permitting all of the gases at all positions of said movable baffle to flow across said superheater before contacting with said superheater, and 70 means to move said movable baffle.

4. A steam boiler having banks of horizontally inclined water tubes, said banks being spaced apart to form a superheater chamber therebetween, a superheater and a reheater in such space, the tubes of the lowermost bank being exposed to the radiant heat of the furnace for substantially their full length, a fixed roof baffle above the lowermost bank to direct the gases toward the high ends of the water tubes thereof, said reheater being positioned above said roof baffle and said superheater being positioned above the high ends of the water tubes of the lowermost bank, a longitudinal baffle in the upper bank to direct the gases from said space into the high end of said bank, a baffle in said space to divert a regulated quantity of the gases from said reheater while permitting all of the gases to flow over said superheater, a movable baffle in said space and movable into either one of two extreme positions, said movable baffle, in one extreme position, being interposed in the direct path of the gases across said space and across said 85 superheater, and in the other extreme position, being interposed in the path of the gases across said space and across said reheater. 90

5. A steam boiler having banks of horizontally inclined water tubes, said banks being spaced apart to form a superheater chamber therebetween, a pair of heating devices in such space, a fixed roof baffle above the lowermost bank to direct the gases toward the high ends of the water tubes thereof, said devices being positioned respectively above said roof baffle and above the high end of the lower bank, a longitudinal baffle in the upper bank to direct the gases from said space into the high end of the upper bank, and a horizontally movable roof baffle above said space and movable from a position above one of said heating devices to a position above the other of said heating devices, whereby the quantity of the gases flowing over the heating device above the fixed roof baffle may be varied while permitting all of the gases to flow at all times over the other of said heating devices, and means to move said movable baffle. 100

6. A steam boiler having banks of horizontally inclined water tubes, said banks being spaced apart to form a superheater chamber therebetween, a pair of heating devices in such space, a fixed roof baffle above the lowermost bank to direct the gases toward the high ends of the water tubes thereof, said devices being positioned respectively 105 110 115 120 125 130

above said roof baffle and above the high end of the lower bank, a longitudinal baffle in the upper bank to direct the gases from said space into the high end of the upper bank, and a horizontally movable roof baffle above said space and movable from a position above one of said heating devices to a position above the other of said heating devices, whereby the quantity of the gases flowing over the 10 heating device above the fixed roof baffle

may be varied while permitting all of the gases to flow at all times over the other of said heating devices, and means to move said movable baffle, said longitudinal baffle being above and spaced from said movable baffle 15 to provide a gas flow space when said movable baffle is positioned between the extreme positions to which it can be moved.

ARTHUR SPYER
